PERCUSSION FUSE

Marc Birkigt, Bois-Colombes, France

Application October 16, 1936, Serial No. 106,033
In Belgium September 11, 1936

3 Claims. (Cl. 102—39)

The present invention relates to percussion fuses for projectiles adapted to turn about their axis along their trajectory, and it is more especially, although not exclusively, concerned with fuses of this kind for projectiles of small calibre.

The object of the present invention is to provide a fuse of this kind which is better adapted to meet the requirements of practice than other fuses of the same kind made up to the present time.

According to an essential feature of the present invention, the striker of the fuse is provided with a locking pin or the like which locks the striker for a certain length of time and which is ejected from its housing by the centrifugal acceleration resulting from the rotation of the projectile about its axis, and said locking element is kept in active position, when the projectile is in the state of rest, by elastic means the action of which upon said locking element takes place in the same direction as that of the forces of inertia developed when there are positive accelerations of the projectile along its trajectory.

Another feature of the present invention consists in interconnecting the striker and the cover plate of the fuse in such manner that said striker, once it is released, is unable to come accidentally into contact with the priming element of the fuse under the effect of the vibrations of the projectile along its trajectory, which might produce a premature explosion of the projectile.

Other features of the present invention will result from the following detailed description of a specific embodiment thereof.

A preferred embodiment of the present invention will be hereinafter described, with reference to the accompanying drawing, given merely by way of example, and in which:

The only figure is an axial section of a percussion fuse made according to the present invention.

The following description relates to the case of a percussion fuse more especially intended for a shell of small calibre adapted to be fired in a fire arm provided with riflings.

The fuse is devised in such manner that the striker with which it is to be provided is locked for the desired period of time by a locking pin or the like capable of being ejected from its housing, under the effect of the centrifugal acceleration resulting from the rotation of the projectile about its axis.

For this purpose, according, for instance to known arrangements, the body of the fuse consists of a metallic piece 1 which is provided at the

rear end with a chamber 2 in which are housed a priming element 3 and a detonator 4, this chamber being closed toward the front by the body of the fuse itself, in which are provided cylindrical bores 5, preferably of increasing diameter toward the nose of the fuse, so as to accommodate and guide a striker 6.

The nose of the fuse is fitted with a cover plate 7.

I provide in the body of the fuse, in a direction at right angles to that of the axis of said striker 6, a housing 8 capable of guiding the displacements of a safety pin 9 the center of gravity of which is in eccentric position with respect to the axis of the fuse, said pin further including, for instance, two branches between which said striker can move in the direction of its axis, said striker 6 being provided with a collar 10, in such manner that its point is kept at a suitable distance from the priming element of the detonator.

According to the essential feature of the present invention, this locking pin 9 is caused to contact with an element capable of keeping it in position and subjected to the action of an elastic system. This elastic system keeps said element in active position when the shell is in the position of rest, and it is arranged to act on said element in the same direction as the forces of inertia when there are positive accelerations of the shell along its trajectory.

Although there are many possible embodiments of such a device, I have found that it is particularly advantageous to make use of that illustrated by the drawing.

The element for keeping the locking pin 9 in position consists of a sliding part 11, for instance of cylindrical shape, capable of moving in a bore 12 extending in a direction parallel to the axis of the fuse, in the front part of body 1, and opening into housing 8. In other words, bore 12 is located in the front part of the fuse, with respect to housing 8. Member 11 is preferably, although not necessarily, fitted with an inclined portion, for instance of conical shape, 13, capable of co-acting with a notch 14, of corresponding shape, provided for this purpose in pin 9.

The elastic system above referred to consists of a spring 15, for instance of the coil type, interposed between element 11 and the bottom of bore 12. Therefore this spring urges the locking element 11 toward the rear of the projectile, by applying it into notch 14.

If desirable, I may also, eventually, provide means for braking the displacements of said element 11 in its housing and therefore for delaying

the release of pin 9, said means being preferably adjustable. For instance I might cause element 11 to coat with a dash-pot of adjustable restricted section.

5 With the arrangement above described, I obtain a percussion fuse the operation of which takes place in the following manner:

As long as the shell keeps, along its trajectory, a sufficient positive acceleration, spring 15 and 10 the forces of inertia acting upon element 11 overcome the thrust exerted by notch 14 upon the end 13 of said element 11. When, as a consequence of the resistance of air to the movement of the shell, the acceleration of the shell drops to a lower value 15 and even to a negative value, this thrust overcomes the action of the elastic system and pin 9, after pushing back element 11, is released and can be expelled, in turn releasing striker 6.

Of course, the position of the point of the trajectory of the projectile where this releasing action takes place will depend, among other things, upon the strength of spring 15 and the value of the angle of cone 13. In any case, this point is at a certain distance from the muzzle of the gun 25 from which the projectile was fired, which, for practical purposes, corresponds to a safety of several meters.

According to another feature of the present invention, which is not necessarily combined with 30 the arrangement just above described, the cover plate 7 of the fuse (which cover plate is then preferably given a concave shape) and striker 6 are interconnected, for instance by securing one to the other. With this arrangement, there is no 35 risk, once the striker is disengaged, of the point thereof coming accidentally into contact with the priming element 3 and causing a premature explosion of the shell, since said point can come into contact with the priming element only after cover 40 plate 7 has been broken as a consequence of the crashing of the shell against an obstacle.

In a general manner, while I have, in the above description, disclosed what I deem to be practical and efficient embodiments of the present invention, 45 it should be well understood that I do not wish to be limited thereto as there might be changes made in the arrangement, disposition and form of the parts without departing from the principle of the present invention as comprehended within the scope of the appended claims.

What I claim is:

1. A percussion fuse which comprises, in combination, a body having a longitudinal axis; a detonator and a striker within said body, said detonator and said striker being movable relative to each other longitudinally of said body for bringing said striker in contact with said detonator, said body being provided with a transverse housing, a member slidable in said housing 55 for normally preventing said relative movement, said member having its center of gravity located in eccentric position with respect to the axis of said body and having an inclined surface at the front side thereof, an element movable in said body in a longitudinal direction thereof adapted to engage said member along said inclined surface so that an outward displacement of said member tends to thrust said element out of the way, and elastic means for urging said element against said member, said elastic means acting on said element in the same direction as the forces of inertia developed by a positive acceleration of the fuse.

2. A percussion fuse which comprises, in combination, a body having a longitudinal axis, a detonator and a striker within said body, said detonator and said striker being movable relative to each other longitudinally of said body for bringing said striker in contact with said detonator, said body being provided with a transverse housing, a member slidable in said housing for normally preventing said relative movement, said member having its center of gravity located in eccentric position with respect to the axis of said body, a bore in said body extending transversely to said housing, said member being provided with a conical hole at the front surface thereof, a member of cylindrical shape having a conical end adapted to slide in said bore and to have its conical end engaged in said hole, said bore extending from said housing toward the front end of said fuse, and a coil spring fitted in said bore so as to urge said cylindrical member outwardly from said bore and toward the rear of said body for keeping said conical end engaged in said conical hole as long as the acceleration is above a predetermined value.

3. A fuse for a projectile intended to move along its trajectory with a rotary movement around its axis, comprising in combination a fuse body, a detonator and a striker within said body, said striker and said detonator being movable relative to each other for bringing said striker in contact with said detonator, means for normally preventing said movement, said means comprising a transverse housing in said body, a locking member slidable in said housing and having its center of gravity located in eccentric position with respect to the axis of said body, an element movable in said body independent of said striker and detonator in a longitudinal direction of said body and adapted to engage said member at the front side thereof and elastic means for urging said element against said member in a direction toward the rear end of said fuse, said elastic means being so tensioned that said member is retained in locking position as long as the acceleration of said projectile increases and said member is moved into unlocking position substantially as soon as the speed of said projectile decreases.

MARC BIRKIGT.
